FILTER CARTRIDGE PACKAGE

Ralph H. Card, Hamburg Township, Livingston County, Mich., assignor to Fram Corporation, a corporation of Rhode Island

Application December 28, 1944, Serial No. 570,092

3 Claims. (Cl. 206—56)

1

This invention relates to a package and dispensing arrangement for filter elements or cartridges used from time to time to replace cartridges which have become saturated with the sludge or contaminant which the filter is designed to remove from the filtrate which passes through it. These cartridges are usually supplied in a box, which may rest upon a table, bench, or other suitable support.

One of the objects of this invention is to provide a package of a plurality of cartridges, one of which at a time may be taken from the pack, for use in a filter.

Another object of the invention is to provide a package of a plurality of cartridges, which may be suspended from above within easy reach of a person desiring to have for use one of the cartridges for placing in a filter.

Another object of the invention is to provide a package in which a gasoline gauge may be provided as a useful part of the package and which may serve as a gauge upon exhaustion of the cartridges in the package.

Another object of the invention is to utilize the gasoline gauge of the package as a suspending means.

Another object of the invention is to provide a package to have a cover which will exclude dirt from the package.

With these and other objects in view, the invention consists of certain novel features of construction as will be more fully described and pointed out in the appended claims.

Fig. 1 is a perspective view of the package.

Fig. 2 is a fragmental sectional view.

Fig. 3 is a perspective view of the supporting member or gasoline gauge.

Fig. 4 is a plan view of the sheet stock wrapper.

In proceeding with this invention, I assemble a plurality of cylindrical cartridges, having an axial center opening in a position so that the axial openings will be in registration or alignment, a gasoline gauge member of rigid construction is placed through the axial opening of the plurality of cartridges and provided with a removable abutment at its lower end and a suspending loop at its upper end whereby the plurality of cartridges may be suspended in a pendant relation from this loop at the upper end of the rigid member. A dust cover or cap may be provided to extend over the uppermost cartridge with a flange to tightly fit about the uppermost cartridge and a perforation to receive the rigid member. A wrapper of sheet material, such as paper, of a length to extend the entire axial

2

length of the plurality of cartridges, is wrapped about the cartridges so as to hold them as a single unit. Some indication is marked on this wrapper to show approximately the line of juncture between the cartridges, and this indication may be in the form of a weakening line which may be easily ruptured for disconnecting one of the cartridges from the package. This wrapper also affords a surface for printing directions or advertising matter which may be desired thereon.

With reference to the drawings, 10 designates a cartridge which will be one of a plurality of cartridges in the package. It consists of a cylindrical wall 11 having end walls 12, 12' with central openings 13, 13' which may be connected by a center tube 14 of the cartridge. Within the cartridge, between the center tube and the cylindrical wall 11, suitable filtering media 15 may be provided. In some cases cartridges of a different construction may be utilized, the essential part of the cartridge being that it have a center opening and some filtering media radially outwardly from this opening. The outside shell 11 is unimportant from the standpoint of the invention here illustrated. The cartridges which are here shown are each equipped with a gasket 16 and washers 17 located between the cartridges which may be utilized in positioning the cartridge in the filter and may of course be assembled in any way with the cartridges which are provided.

Two mutually cooperative means of assembling the plurality of cartridges in a unit package formation are provided. One of these means is a wrapper of sheet material 20 (see Fig. 4) which I have here illustrated as a sheet of paper of a length equal to substantially the length of the axially assembled cartridges, one in contact with the other. The width of this sheet of material is a little greater than the circumference of a cartridge, so as to provide for a portion 21 to be overlapped by a portion 22 at the opposite marginal edges. Some sort of cement will be utilized for attaching these overlapping portions 21 and 22 so that all of the cartridges will be wrapped by this single sheet of paper. Tightly wrapping the cartridges in this manner serves to hold them in axial alignment. At the line of juncture between the cartridges I will provide an indicating line 23 to extend circumferentially about the wrapper and which will indicate the axial length of the cartridge or the junction between cartridges. This line 23 may be conveniently formed by weakening this portion, such for instance as by spaced

perforations. The name of the package may be placed in one of the areas as 24 while other advertising material may be placed in the areas 25, 26 or 27. Instructions may be placed in the areas 28, 29, 30 and 31, that the manner of using the package may be given to the person who is to use the same.

The other means of holding the plurality of cartridges in assembled relation is a rigid member 35 which is in the form of a rectangular wooden stick, although any rigid member may be provided. This stick is passed through the center tubes 14 of the assembled cartridges and has a hole 36 at its lower end for the reception of a cotter pin 37 which may be removably positioned in this hole. A washer 38, having an opening 39 of a shape to receive the stick or rigid member 35 is positioned above the cotter pin and forms an abutment upon which the lowermost of the plurality of cartridges rests. Thus, when the stick is suspended, this abutment will serve as a means for holding all of the cartridges on a stick in assembled relation. At the upper end of this rigid member another hole 40 is provided, in which there is located a loop 41 of bail like formation so that the package may be suspended from some hook 50 or overhead support.

This rigid member 35 is marked in such a manner that it may be used as a gas gauge by reason of graduations 42 provided on opposite sides of its lower portion so that the same may be utilized as a gauge. Advertising material may be provided at 43 on the alternate sides of the rectangular member. A cover 44 having a central perforation of a size and shape to receive the rigid member 35 is positioned on this rigid member below the loop 41 and has a cylindrical flange 45 to extend down over the wrapper which is positioned about the cartridges. This cover serves as a means for holding the upper edge of the wrapper in wrapped position, and serves to prevent dust from accumulating on the horizontal surface of the upper cartridge. Its squared opening 46 also would assist if the cover were made of sufficiently heavy material to resist the turning of the upper cartridge by any torsion being applied to the lowermost cartridge for the rupturing of the wrapper about the indicating line 23.

In use, the package will be suspended from some overhead support 50. If it is desired to extract the lowermost cartridge from the package, one hand will be placed upon the cartridge above the lowermost cartridge, and another hand 47 upon the lowermost cartridge. A relative twisting motion about the axis of the cartridge as a center will serve to rupture the wrapper along the lowermost line 23 whereby the lowermost cartridge is then free from being bound in assembled position by the wrapper. It is then merely necessary to remove the cotter pin 37 from the hole 36, removing the washer 38 and withdrawing the lowermost cartridge from the rigid member or oil gauge 35. After withdrawing the lowermost cartridge the washer is replaced and the cotter pin replaced, so as to hold the remaining cartridges in assembled position, which will slide downwardly on the rod 35 to be supported by the washer. The wrapper will be stripped from the cartridge which is removed from the pack, and the cartridge is ready for use. Gaskets 16 and washers 17 which are required are assembled with the cartridge for use. If another cartridge is required, the same operation

will be again repeated. When the last cartridge is used, the rigid member 35 may be utilized as a gas gauge, which is marked at 42 appropriately for indicating the quantity of gasoline which is in the tank into which it will be placed.

I claim:

1. A filter cartridge package comprising a plurality of cartridges, each having a central axial opening positioned with said openings in alignment, a sheet of material wrapped about said cartridges to hold the cartridges assembled as a unit, said sheet of material being weakened at its area adjacent the junction line of the cartridges, sufficient for rupture upon rotary movement of the cartridge and wrapper about said central axis, a rigid member extending through said aligned openings, means carried by the lower end of said member to support said cartridge and means at the upper end of said member to support said package, in pendant relation.

2. A filter cartridge package comprising a plurality of cartridges, each having a central axial opening positioned with said openings in alignment, a sheet of material wrapped about said cartridges to hold the cartridges assembled as a unit, said sheet of material being weakened at its area adjacent the junction line of the cartridges, sufficient for rupture upon rotary movement of the cartridge and wrapper about said central axis, a rigid member extending through said aligned openings and means at the upper end of said member to support said package and means at the lower end of said member to form an abutment for the cartridges to rest upon and be supported thereby.

3. A filter cartridge package comprising a plurality of cartridges, each having a central axial opening positioned with said openings in alignment, a sheet of material wrapped about said cartridges to hold the cartridges assembled as a unit, said sheet of material being weakened at its area adjacent the junction line of the cartridges, sufficient for rupture upon rotary movement of the cartridge and wrapper about said central axis, a rigid member extending through said aligned openings and provided with a hole near one end, a removable pin in said hole, an abutment engaged by one cartridge and prevented from movement axially of the member by said pin, whereby to support said cartridges when suspended by said member, a loop attached to the other end of said member for suspending said package, and a cover extending over a cartridge at the other end and having a perforation to receive said member and a flange extending axially of the package and externally of said wrapper.
